BALLOON ENVELOPE MATERIAL AND METHOD OF MANUFACTURING THE SAME

Hans Strobl, Berlin-Tempelhof, Germany, assignor to Luftschiffbau Zeppelin G. m. b. H., Friedrichshafen, Bodensee, Germany

Application January 24, 1935, Serial No. 3,360
In Germany June 23, 1930

4 Claims. (Cl. 154—2)

My invention relates to balloon envelope material as for example for gas cells of gas inflated airships and the like and to the method of manufacturing such material. The present application is a continuation in part of my application Serial No. 544,167, filed June 13, 1931.

Lately it has become usual to manufacture balloon envelope material from fabric combined with skins of animal provenience, both materials being glued together by an adhesive comprising gelatine, isinglass or similar substances with an admixture of softening substances such as glycerine, Turkey red oil or the like.

According to my invention I use only staple fabric without any animal skins or the like, but I impregnate the fabric with liquid substances only. First I impregnate the fabric with a substance insoluble in water, such as india rubber solution, a cellulose product, for instance cellulose acetate or cellulose nitrate, or the like. This impregnation rendering the fabric resistant against weather influences may be applied to the fabric from one side only or from both sides; I prefer to impregnate from one side only but to have the interstices of the fabric filled more or less with this first impregnation substance. Normally the amount of substance applied to the fabric should be such that an uninterrupted surface layer of such waterproof material results. Of course, instead of substances entirely insoluble in water such substances may be used also which are nearly insoluble or mixtures of both kinds.

Then I provide one side of the impregnated fabric with a second impregnation, this time composed of gelatine, of casein, isinglass or a similar substance with an admixture of a softening agent such as glycerine, Turkey red oil or the like. These substances may be applied as a mixture or separately in any number of coatings. The weight proportion of the gelatinous material to the softening agent should be from 50:50 to 33 1/3:66 2/3, which means that at least the same weight amount of softening agent should be applied as gelatinous material is used. This second impregnation which is to be made on the second surface of the fabric may again be applied in such quantity that a second uninterrupted surface layer of such gas-tightening substance results.

At last I add to the material which is now impregnated twice a third layer preferably of fibre or the like, which is connected to the other layers by means of the impregnating substances themselves, which can be done by applying this fibre

layer before the prior impregnations have dried, or any well-known adhesive may be used therefor. This layer of fibre may be applied loosely or as a fabric, as circumstances may afford. Cotton or linen fibre for example are suitable for this layer. This fibre layer can be applied to one side or to both sides of the balloon envelope material; if applied to one side only it should be the side which carries the second (gas-tightening) impregnation, as this needs protection more than the weather-proof surface.

As the first impregnation for rendering the original fabric resistant against weather-influences serves more or less also for filling the interstices of the fabric, this means a reduction in the necessary amount of the gas-tightening substance for the second impregnation. The third layer consisting of fibre is most important because it protects the impregnation layer or layers against influences from outside, especially mechanical influences such as rubbing and the like. It is very valuable to have such protection on the side of the second (gas-tight) impregnation, but if circumstances should afford both sides may be so protected.

The new material attained by my method of manufacture has great advantages over the old materials. The special sequence of procedures causes a high quality material which is gas-tight, light and resistant against wear.

Instead of using one original layer of fabric, two or more such layers may be used. For instance two thin fabric layers can be impregnated in the first manner with the substance rendering the material resistant against weather influences and then both may be united by means of an intermediate impregnation of the second kind for making the material gas-tight serving at the same time for gluing the two layers together. This second impregnation which is hygroscopic is then enclosed by the weather-resistant coatings so that practically a minimum of water can only be absorbed.

To the impregnating substances which are subject to decomposition by outer influences (substances of animal provenience as gelatine or the like) I prefer to make a preserving agent, as for instance creosote or the like.

In certain cases it may be found desirable to further add to the balloon envelope material manufactured according to the new method of my invention—as explained above—an outer coating of oil or lacquer, which may be applied in any well-known manner on top of the fibrous layer and/or on the surface which possibly does

not carry any fibre. Furthermore, aluminium dust or powder may be strewn on this oil or lacquer coating to remove its stickiness and to render the surface of the material reflecting to light 5 and heat rays.

In the drawing an example is represented embodying my invention.

The staple fabric is indicated at 1. The weatherproof impregnation 2 fills the interstices 10 of the fabric 1. In the present example the quantity of the impregnating substance is assumed to be so rich that the upper surface of the impregnating layer is plane. But of course, in certain cases it may suffice to apply only so much 15 material that the fabric 1 is just soaked up to its upper surface so that the surface of the impregnation is wave-like following the surface of the fabric itself. The second impregnation 3 of the gas-proofing composition is applied to the other 20 side of the fabric. There is a protective layer of fibre 4 assumed to be applied to both sides of the balloon material.

I do not want to be limited to the details described or shown in the drawing as many variations will occur to those skilled in the art.

What I claim is:

1. Balloon envelope material comprising a water-proofed staple fabric, a gas-proofing gelatinous coating including a softening agent and 30 having adhesive properties applied to the side of said fabric, and a wear-resisting layer of fibre

secured to the fabric on the gas-proofed side thereof.

2. Method of manufacturing weather-proof and gas-tight balloon envelope material which consists in first impregnating a staple fabric 5 with a liquid water-proofing composition, then applying a gas-proofing gelatinous composition coating to one side of the fabric, and thereafter affixing a wear-resisting fibrous layer to the gas-proofed side of the fabric.

3. Method of manufacturing weather-proof and gas-tight balloon envelope material which consists in first impregnating a staple fabric 10 from one side with a liquid weather-proofing composition, then applying on the other side a 15 gas-proofing impregnation of gelatinous coating material incorporating a softening agent, and thereafter affixing a protective fibrous layer to the gas-proofed side of the fabric.

4. Method of manufacturing weather-proof and gas-tight balloon envelope material which consists in first impregnating a staple fabric 20 from one side with a weather-proofing liquid rubber composition, then applying on the other side a gas-proofing impregnation of gelatinous 25 coating material incorporating a softening agent and having adhesive properties, and affixing to the gas-proofing impregnation through its adhesive properties a protective fibrous layer.

HANS STROBL.
